UNITED STATES PATENT OFFICE.

ELIZABETH GALBRAITH, OF FAYETTEVILLE, ARKANSAS.

COMBINED HOOD AND CAPE.

1,119,268.

Specification of Letters Patent.

Patented Dec. 1, 1914.

Application filed December 4, 1912. Serial No. 734,904.

To all whom it may concern:

Be it known that I, ELIZABETH GALBRAITH, a citizen of the United States, residing at Fayetteville, in the county of Washington and State of Arkansas, have invented certain new and useful Improvements in Combined Hoods and Capes, of which the following is a specification.

The garment which is the subject of the present invention is designed to serve as an emergency rain-cape, and the object of the invention is to provide a garment of this kind which can be cheaply made, and which is capable of adjustment to different sizes. Oiled paper is preferably used in constructing the garment, and it is intended to provide a garment which may be distributed through vending or "slot" machines.

The invention also has for its object to provide the garment with a securing device of especial design and especially adapted to connect the opposite side portions of the cape together.

A further object of the invention is to provide means for drawing the hood close around the throat of a wearer.

With these objects in view, the garment includes a cape portion to which is suitably attached a hood portion and a draw string is provided upon the hood portion. Securing devices are provided upon the cape portion and these devices include parallel slits provided in one side of the cape portion and preferably reinforcing members located adjacent to the slits, the said members also having slits which register with the slits in the cape portion. The cape portion is also provided at one of its edges with tongues, adapted to be inserted through the slits hereinbefore mentioned. These tongues are provided with slits through which the free ends of the tongues are adapted to be inserted, whereby they are secured for holding the cape in close proximity about the body of a wearer.

In the accompanying drawing, Figure 1 is a perspective view of the combination garment. Fig. 2 is a detailed sectional view of portions of the garment showing the securing devices in position.

Corresponding and like parts are referred to in the following description and indicated in all the views of the accompanying drawing by the same reference characters.

The garment includes a cape 1 to the up-

per end of which is suitably secured a hood 2. This hood 2 is preferably secured by means of a line of stitching 2'. The cape and hood may be of any desired pattern and may be connected together by sewed seams or other means. As already stated, oiled paper is preferably employed in the construction of the garment. The lower portion of the hood 2 is provided with a series of eyelets or openings 3 through which is threaded a draw string 4. The free ends of this string are located at the forward portion of the hood and may be tied together whereby the lower portion of the hood may be drawn close around or against the neck of a wearer of the garment.

One side portion of the cape 1 is provided with slits 5. These slits are arranged in pairs, the members of the pairs of slits are spaced slightly from each other as clearly illustrated in the several figures of the drawing. In practice it is preferred to reinforce the slitted portion of the cape by strips 6. These strips may be cemented, stitched or otherwise secured in position, and they are provided with slits which register with the slits provided in the cape. Tongues 10 are secured to the opposite side portion of the cape 1, from that side which is provided with the slits 5. These tongues are formed from material substantially the same as that of which the garment is made, and they possess a certain amount of rigidity and retain a certain degree of flexibility. The tongues 10 are provided with slits 11, these slits being located between the ends of the tongues and beyond the edge of the side of the cape 1. The tongues 10 are preferably tapered longitudinally as best illustrated in Fig. 1 of the drawing.

It is of course understood that the cape 1 is adapted to rest over the shoulders and upper portion of the body of a wearer, and when in this position the free ends of the tongues 10 are inserted through the slits 5, and the free ends of the said tongues are then folded back over the intermediate portions of the tongues and the extremities of the tongues are inserted through the slits 11 of the tongues. Therefore the free ends of the tongues 10 are held and the intermediate portions of the said tongues engage the material of the cape 1 which is located between the members of the pairs of slits 5.

It will be noted that three sets of slits 5 are provided, spaced different distances

from the edge of the cape. Either set of slits may be used, which makes the garment adjustable to different sizes.

I claim:

- 5 A garment comprising a cape, a hood provided with a downward extension stitched to and forming a yoke for said cape, said yoke extending over the forward portions of the shoulders of the cape, the front lower portions of said hood constituting free flaps,

and means carried by said flaps for drawing the same in close proximity around the throat of the wearer.

In testimony whereof I affix my signature in presence of two witnesses.

ELIZABETH GALBRAITH.
